STENCIL SCREEN FRAME

Charles J. Hannah and Russell D. La Salle,
Paterson, N. J.

Application June 4, 1947, Serial No. 752,486

4 Claims. (Cl. 101—127.1)

1

This invention relates to an improvement in a frame for screening used in textiles.

The old style of frame and the frame in common use is made of wood and is not durable, warps readily and as a result of the warping the pattern or design is distorted and results in substantial damage due to improper design and due to the cost of rapid replacement of frames as the said frames are sent out to various shops to be used in printing and are given rough usage.

Our invention has to deal with the construction of a frame made up in four sections preferably of magnesium, as that material is light and has a replaceable insert principally made of wood, which inserts are inexpensive and can be replaced from time to time. It is possible to make the frame in a single die cast. The frame does not warp and will last for years and is not expensive to manufacture and has been found not to warp or distort the pattern, as a result it is cheaper than using the present type of frame.

One form of our invention is illustrated in the accompanying drawings in which Figure 1 is a cross section view of the screening frame in its applicable use; Figure 2 is a partial prospective view of a screening frame; Figure 3 is a fragmentary face view of same; Figure 4 is a cross section of a modified form of a screening frame and Figure 5 is another modified form of a screening frame and Figure 6 is another modification of the form of my invention.

Reading on Figures 1 to 3 inclusive, 10 is the frame made up of four equal sections 10a, each having a semicircular face portion 11, side portions 12 and connecting web 13 and hand grip 14, which said hand grip goes completely around the frame for easy manipulation. Each one of the four sections of the frame has a mitred edge 10b, and therewith allowing one to build an exact square frame. In order to hold the four sections together, four angle iron pieces 9 are used. The same are riveted to one section of the frame as at 8 and held together at the other end to the second member 10a by a screw 7, thus enabling an easy means of detaching the frame 10 and inserting a new wedge member 16 when desired. 15 is a dove tailed groove in the semicircular portion 11 of frame 10, and 16 is a wooden wedge member; 17 is the screen carrying type of design 18 and is tacked on to member 16 by nails 19, the material to be printed, is shown as 20, and 21 is the supporting table; 22 is a squeegee, and 23 is the dye, 24 is a mitred edge of member 16.

Reading on Figure 4, 25 is the frame of the modified form of the invention, 26 is the circular

2

opening in the said modified form of the invention, 27 is a rod insert.

Reading on Figure 5, 28 is the tubular frame of another modified form of the invention with a dove tailed groove 29, and a dove tailed wooden insert 30.

The most conventional form of material as previously stated and the most desirable form is magnesium. However, any light material such as 10 aluminum or any lighter alloy can be used; however, the preference is given to magnesium due to the lightness of the metal and the preference in having the frame made of an exceptionally light material. However, any of the metals or 15 their alloys do not warp and besides by applying the screen to the type of frame herein described with a rounded surface, the said screen will not be damaged by the said frame.

The only portion of the invention which must 20 be replaced from time to time will be the wedge portion 16, or its counter portions 27, 30. The said wedge portion 16, or its counter portions 27 and 30 are slipped into the end and side portions of the frame and due to its mitred edges form a 25 perfect junction when the inserts are completed. The material is then tacked to two of the edges on the said frame at the wood portion by use of thumb tacks or similar fastening means and the material is then stretched across the frame and tacked on the other edges by similar means.

Due to the construction of the frame having a 30 rounded surface, there are no sharp edges on the frame member to contact the screen and there should be no breaking of the screen at the point of contact with the frame or any taking place during the operation by any pressure exerted during the transfer operation on the screen and will never interrupt the firm contact between the frame member and the screen on account of the 35 wedge shaped edges of the wooden insert as the insert locks itself automatically in place and prevents any loosening of the units in relation to each other.

We have shown this frame in a modified form 40 as shown in Figure 4 and in that modified form the insert is round.

We have also shown the frame in a modified form as shown in Figure 5 made of tubular iron with an insert similar to the wedge shown in the 45 preferred form, Figures 1, 2 and 3.

As illustrated in Figure 6, an open frame 31 is used with a reinforcing web 32, having a round recess 33. Instead of a solid wedge member a 50 rope 34 is used and it is tucked in with the material 17, from the outside of the frame. In this

case a solid piece of frame may be applied, and replacing of wedging member 34 is unnecessary as the material 17 is not fixedly attached to same and therefore no replacement of member 34 is required as in the previously described forms of invention.

The recesses 15 in the various frame sections 10a are in the lower portions of such sections and are coextensive in length with the sections, opening through the ends of the sections. Such recesses 15 have mouths which open generally downward in order to expose the wood or other nail-receiving strips 16. These recesses 15 may in cross-section be dove-tailed or any other suitable geometric form in which some inner portions of the recesses are wider than the mouths so as to prevent the entrance or removal of the strips 16 through the mouths, inasmuch as the strips 16 are cross-sectional complements of the recesses 15. Therefore the strips 16 are introducible into the recesses 15 only when the sections are disassembled and only by a longitudinal sliding movement of the strips endwise of the recesses. The strips 16 are exposed on the ends of the sections 10a and the mitering or beveling 10b of the ends of the sections cooperates with the recesses 15 and strips 16 constructed as described in that when the beveled ends 10b of the sections are assembled into the frame the ends of adjoining strips 16 are abutted. In this way, without the aid of any additional fastenings, the strips 16 are confined in the recesses 15 and also prevented from creeping or accidental longitudinal movement therein which might adversely affect the taut condition of the stencil screen 17 which is affixed to the strips 16 by the nails or other fastenings 19.

This construction also leads to another advantageous result in that the strips 16 instead of being of the large cross-section of the entire frame may be made of a relatively small cross-section occupying a cross-sectionally small recess 15 in the lower portion only of the frame section. In other words the reinforcement which the strips 16 receive from the endwise abutting in the beveled or mitered end joints 10b enable the use of strips 16 of a very small cross-section only deep enough to receive the nails or other fastenings 19. In this way substantial material is saved in the strips 16 and the frame lightened correspondingly, which fact cooperates with the hollow section of the metal frame which is another advantage of the invention.

A cross-sectionally small recess 15 also enables the recess to be diagonally disposed so that the lower mouth thereof will not open vertically downwardly but will face outwardly of the lowest point on the rounded bottom edge 11 of the frame. As shown in Figure 2 this construction removes the nail heads 19 to a position above contact with the material 20 to be printed.

In order to produce this result it will be noted that the lower web 13a unlike the top connecting web 13 is inclined laterally between the two upstanding walls 12 with its higher end merging with the outer side wall 12 and its lower end merging into the lower portion of the inner side wall 12. This results in the construction in which the inner side wall 12 is of greater vertical height than the outer side wall. Moreover the lower connecting web 13a is substantially thicker than the upper web 13 in order to accommodate the recess 15 and has substantial masses of material at the sides of the recess 15 which are adjacent the lower end portions of the spaced side

walls 12. This makes for a more rigid construction in an article wherein lightness is a prime requisite, which is the reason for the hollow cross-sectional construction of the sections involved in the horizontally spaced walls 12 and in the vertically spaced webs 13 and 13a.

Incidental to these constructions but contributing to the same unitary result, are the angled end connecting pieces 9 which are accommodated within the space between the hollow-walled construction 12, 13, 13a while the top webs 13 actually receive the fastenings 8, 7 by which these angle retainers 9 are affixed to adjacent sections so that the sections may be held abutted at their mitered joints 10b with the advantages heretofore described; it being understood that the hollow-walled construction enables the angle retainers 9 to be obscured within the hollow walls and thus not to interrupt the smooth continuity of the external surfaces of the frame sections which is so desirable a characteristic in the art of stencil frames.

While we have illustrated our invention in one form only and as made with specified materials, we do not intend to limit ourselves to that particular design, method and materials as it is apparent that other designs, methods and materials may be employed in obtaining the same results within the scope of our claims and without departing from the scope or spirit of our invention.

We claim:

1. An improved stencil frame for use with stencil screens attached to the frame by headed fastenings comprising a plurality of sections having beveled ends adapted to be abutted together to constitute a generally rectangular open frame, retainer means for securing the sections together, said sections being hollow and each comprising inner and outer spaced substantially vertical side walls, said inner side wall extending down to a lower elevation than the lower end of said outer side wall, an upper web connecting the upper ends of said inner and outer side walls, an inclined lower web extending between the lower ends of said inner and outer side walls and having thickened portions merging with the lower ends of said side walls and also having a recess extending substantially the length of the section and opening through the ends of the section, said lower web having a transversely-rounded bottom surface adapted to receive marginal portions of the screen, said recess having a mouth opening through the rounded bottom surface outwardly of the lowest point of said rounded surface adapted to receive outwardly and upwardly extending parts of the marginal portions of the screen, said recess having at least a pair of flat walls and an inner portion wider than said mouth, and a strip of nail-receivable material of substantially the same cross-section as that of said recess slidably longitudinally into and out of said recess and exposed in the outer lower portion of said rounded bottom surface through said mouth adapted to receive into said strip through said mouth the screen fastenings with the heads of the fastenings lying above the lowermost point of the rounded bottom surface by which the frame is supported and which contacts the material to be printed.

2. An improved stencil frame for use with stencil screens attached to the frame by headed fastenings comprising a plurality of sections having beveled ends adapted to be abutted together to constitute a generally rectangular open frame, said sections being hollow and each comprising inner and outer spaced substantially vertical side

walls, said inner side wall extending down to a lower elevation than the lower end of said outer side wall, an upper web connecting the upper ends of said inner and outer side walls, an inclined lower web extending between the lower ends of said inner and outer side walls and having thickened portions merging with the lower ends of said side walls and also having a recess extending substantially the length of the section and opening through the ends of the section, said lower web having a transversely-rounded bottom surface adapted to receive marginal portions of the screen, said recess having a mouth opening through the rounded bottom surface outwardly of the lowest point of said rounded surface adapted to receive outwardly and upwardly extending parts of the marginal portions of the screen, said recess having at least a pair of flat walls and an inner portion wider than said mouth, and a strip of nail-receivable material of substantially the same cross-section as that of said recess slideable longitudinally into and out of said recess and exposed in the outer lower portion of said rounded bottom surface through said mouth adapted to receive into said strip through said mouth the screen fastenings with the heads of the fastenings lying above the lowermost point of the rounded bottom surface by which the frame is supported and which contacts the material to be printed, and retainer means for securing said hollow sections in end abutting relation comprising angle pieces having legs lying wholly within the interiors of adjacent hollow sections, fastenings for securing the retainer means to adjacent sections, one at least of said fastenings being removable and insertible from the exterior of a section.

3. An improved stencil frame for use with stencil screens attached to the frame by nails comprising a frame body having transversely-rounded bottom surfaces and recesses having at least a pair of flat walls with mouths opening on the outer lower portions of the rounded bottom surfaces outwardly of the lowest point of said surfaces with marginal portions of the screen adapted to be stretched under and in contact with said rounded surfaces and upwardly and outwardly across said mouths, the width of the mouths of said recesses not exceeding the width of the bottoms of said recesses, and nail-receivable strips in said recesses flush with the rounded bottom surfaces and exposed through said mouths to receive the screen attaching nails with the nail heads above the plane of the

stretched stencil screen whereby the components of the stretching stress of the screen acting through the fastenings will tend to lock the strips in place in the recesses.

- 5 4. An improved stencil frame for use with stencil screens attached to the frame by nails comprising a frame body having bottom supporting surfaces and rounded surfaces outwardly of said bottom supporting surfaces curving from the outer portions of the bottom supporting surfaces upwardly and outwardly, said frame body having recesses with at least a pair of flat walls and with mouths opening outwardly and downwardly through said rounded surfaces with the axes of the depths of the recesses diagonal to the bottom surfaces of said frame, marginal portions of the screen adapted to be stretched under and in contact with both said bottom and rounded surfaces and upwardly and outwardly across the mouths of said recesses, the width of the mouths of said recesses not exceeding the width of the bottoms of said recesses, and nail-receivable strips wholly within said recesses flush with the rounded surfaces and exposed through said mouths to receive the screen attaching nails with the nail heads above the plane of the stretched stencil screen whereby the components of the stretching stress of the screen acting through the fastenings will tend to lock the strips within said 20 diagonally disposed recesses.
